UNITED STATES PATENT OFFICE

2,493,908

HAT FASTENER

Edna M. Baker, Chicago, Ill.

Application June 3, 1947, Serial No. 752,082

2 Claims. (Cl. 132—65)

1

This invention relates to certain new and useful improvements in hat fasteners.

More particularly, my invention has as an object to provide a novel device which is relatively simple in construction, inexpensive in manufacture, efficient in use, and one adapted to be attached to a hat, particularly a woman's hat, for the purpose of holding the hat in place upon the head of the wearer.

Another, and equally an important object of the invention, is to construct a device of this character so that when in use it is invisible and is capable of being applied to, and removed, from the usual conventional type of hat wherein there is provided in such hat a hat band.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a perspective view showing a preferred form of the invention associated with a woman's hat of conventional design;

Fig. 2 is a plan view of a mounting plate embodied in the invention;

Fig. 3 is a fragmentary perspective view of a hat showing the method of associating the mounting plate with the hat band thereof;

Fig. 4 is a perspective view similar to Fig. 3 showing the mounting plate in a partially attached portion;

Fig. 5 is a sectional detail view taken substantially on line 5—5 of Fig. 4 but showing the mounting plate completely mounted upon the hat band; and

Fig. 6 is a plan view of the invention shown attached to a hat band.

A preferred form of my invention is shown in the drawings and is there indicated at 10.

The hat attachment embodying my invention comprises a comb-like member 11 of relatively thin flexible material and which may be made of metal, Celluloid or any other suitable and relatively thin material.

The comb-like member 11 includes two substantially parallelly extending attachment arms 12 each having their free outer end portions diverged slightly and having outwardly extending hooked portions 13. Formed integrally with the body 11 are a plurality of teeth 14.

The hat attachment includes a mounting plate 15 of flat elongated formation and provided in adjacent corners with perforations 16.

2

An attachment pin is indicated at 17. One end portion of this pin provides an eyelet, or ring 18, projected in one of the perforations 16.

A split ring 19 is mounted in the other perforation 16.

As shown, the pin 17 is somewhat longer than the length of the plate 15.

Formed in the plate 15 are spaced webs 20. These webs 20 are formed in the plate 15 by slitting the plate as at 21.

The plate 15 is removably mounted to the hat band 22 of the hat 23 by projecting the pin 17 through the hat band 22 so that when the pin is projected through the hat band in a direction

15 from the inner side thereof, the projecting portion of the pin will extend beyond the plate 15 as shown in Fig. 4. This portion of the pin indicated at 24 is then passed into the ring, or eyelet 18, after which it is bent back upon the plate as shown in Fig. 5. In this manner the mounting plate 15 may be removably attached to the hat band.

The pin in effect acts as a hinge for the plate 15 to facilitate positioning the plate 15 in a convenient position whereby the arms 12 may be projected beneath the webs 20, it being pointed out that the material from which the plate 15 is formed permits the flexing outwardly of these webs 20 when the arms 12 are applied to the plate for positioning beneath the webs 20.

With the comb 11 mounted to the hat as shown in Fig. 1 it may be projected into the hair of the wearer of the hat to securely hold the hat in place upon the head.

35 As it is intended that the comb be formed of a flexible material, it will be apparent that the arms 12 may be compressed toward each other during their movement into position beneath the webs 20 and when released these arms will expand to bear against the webs 20 and thereby to releasably hold the comb 11 in position.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. A hat attachment comprising a mounting plate having a pair of spaced aligned web por-

tions of flexible material and provided at opposite corresponding corners with perforations, a pin element having an eyelet mounted in one of the perforations, a split ring mounted in the other perforation and adapted to be threaded upon said pin element, said pin element being adapted to be bent back upon itself to embrace the split ring, in combination with a comb having parallel attaching legs adapted for positioning beneath the said web portions.

2. A hat attachment comprising a relatively flat thin flexible elongated plate having a pair of spaced aligned webs formed therein and in opposite corresponding corners a pair of perforations, a pin having an eyelet connected to said plate through one of said perforations, a split eyelet connected to said plate through the other of said perforations and adapted to embrace and cooperate with the pin to attach the plate to a band of a

hat, in combination with a comb having a pair of spaced attaching arms adapted for positioning beneath said webs.
